WITNESS:

BY Victor J. Evans

ATTORNEY

UNITED STATES PATENT OFFICE.

CHARLES P. SALGEE, OF PHILADELPHIA, PENNSYLVANIA.

MEANS AND METHOD FOR MAKING SIGNS.

1,390,166.

Specification of Letters Patent.

Patented Sept. 6, 1921.

Application filed September 18, 1920. Serial No. 411,118.

To all whom it may concern:

Be it known that I, CHARLES P. SALGEE, a citizen of the United States, residing at Philadelphia, in the county of Philadelphia and State of Pennsylvania, have invented 5 new and useful Improvements in Means and Methods for Making Signs, of which the following is a specification.

The invention relates to signs and more particularly to road signs such as are generally seen upon the highway to indicate danger, act as warnings, or for some other similar purpose and the object of the invention is to provide a means for making 10 such signs upon poles such as are generally found on the highway and for stenciling signs upon the object which is to bear the same.

Among other features the invention comprehends the use of a stencil whereby signs of distinctive character can be readily and quickly stenciled upon a pole and to this end various different kinds of signs may be employed for different purposes as for instance 15 signs indicating car stops and warnings and other signs for automobilists and persons operating different forms of vehicles over the highway.

With the above objects in view, use is 20 made of a suitable member arranged to encircle the pole and having cut out portions so that when a coat of paint, whether it be of the ordinary variety or a luminous paint, is subsequently painted over the member, and 25 the member then removed, those parts of the pole covered by the member will appear as before, whereas those parts seen through the cut out portions of the member will show the paint in the particular shape or design 30 of the member.

In the further disclosure of the invention reference is to be had to the accompanying drawings constituting a part of this specification, in which similar characters of reference denote corresponding parts in all the 45 views, and in which,—

Figure 1— is an elevation of the stencil.
Fig. 2— is a plan view thereof.

Fig. 3— is a fragmentary elevation of a 50 pole showing the form of sign produced with the stencil set out in Figs. 1 and 2.

Figs. 4, 5, 6, 7, 8 and 9, are all fragmentary elevations of poles showing different forms of stencils that may be produced.

55 Referring more particularly to the views, I provide a cylindrical stencil member 10

which preferably consists of a plurality of semi-circular pieces 11, each of which at their upper and lower ends are provided with bands 12, the rear ends of which are 60 hinged together as at 13 with the front ends of the bands on one of the members carrying bolts 14 for receiving winged nuts 15 while the front ends of the bands on the other member are provided with extensions 16 and 65 in fact terminate in such extensions and which may be of a flexible character and provided with apertures 17. In the application of the stencil member to a pole the two pieces are swung into open position so that 70 they can be conveniently arranged to encircle the pole and then by removing the winged nuts from the bolts and passing the bolts through certain of the apertures 17 after the pieces have been tightly fitted around the 75 poles, the application of the winged nuts to the projecting ends of the bolts will secure the stencil member rigidly in position. Each of the pieces 11 has cut out portions 18 which may be of any desired shape or configuration 80 and certain letters may be cut out in the pieces to indicate the words "Car stop" for instance. Now when paint or some suitable pigment is applied it will be seen that the parts of the pole appearing through the cut 85 out portions will be covered with the pigment while those parts covered by the stencil member will not be covered or coated by the pigment. Thus when a stencil such as the one shown in Fig. 1 for instance, is subsequently removed, a sign such as shown in Fig. 3, will result, and it will of course be apparent that with the stencil members made with different shaped cut out portions, that various different shapes of signs such as 90 those shown in Figs. 4 to 9 inclusive, may be obtained. By standardizing certain signs to indicate certain warnings of signals or danger places, it will be apparent that persons approaching on a vehicle by simply noting the particular shape of a sign will immediately be apprised of the particular danger or warning as to that danger farther on the road. While I have shown a particular form 95 of stencil member, I lay particular stress upon the method of making a sign, namely by stenciling the same upon a pole. The present well known and usual method of 100 making signs on poles along the highway is to paint each sign in detail or to apply 110 printed metal signs to the pole. This is an expensive method of installing signs along

the highway and when the signs are individually painted without a stencil they do not always look alike and uniformity cannot be obtained.

5. With my method of stenciling signs upon a pole, absolute uniformity is secured and the method can be carried out quickly and expeditiously and at very little cost.

Having described my invention, I claim—

10. A means for making signs comprising a cylindrical stencil member consisting of a pair of semi-circular elements having a plu-

rality of openings formed therein, bands secured to the upper and lower ends of one of said elements, bolts carried by one end of said bands, bands secured to the upper and lower ends of the opposite element hingedly connected to the bands aforesaid and provided with flexible apertured extensions adapted to receive said bolts and winged nuts mounted on the other ends of said bolts and adapted to engage said extensions.

In testimony whereof I affix my signature.

CHARLES P. SALGEE.
